UNITED STATES PATENT OFFICE.

CARL AMUNDSON, OF SLAYTON, MINNESOTA.

CLEANING ATTACHMENT FOR HARVESTERS.

No. 870,534.

Specification of Letters Patent.

Patented Nov. 12, 1907.

Application filed April 19, 1907. Serial No. 369,133.

To all whom it may concern:

Be it known that I, CARL AMUNDSON, a citizen of the United States, residing at Slayton, in the county of Murray and State of Minnesota, have invented certain new and useful Improvements in Cleaning Attachment for Harvesters, of which the following is a specification, reference being had to the accompanying drawings.

My invention relates to improvements in harvesting machinery, and particularly to binders and like machines; and an object of my invention is to provide a machine of this character with an attachment for keeping its discharge arms clean of the straw and the like which collects upon the arms in the ordinary use of the machine.

15 In the drawings illustrating the principle of my invention and the best mode now known to me of applying that principle, Figure 1 shows so much of a binder equipped with my attachment as is necessary to illustrate my invention; and Fig. 2 shows my new attachment in perspective.

While only one discharge arm *a* is shown in the drawing, it will be understood by all skilled in this art that there are two, side by side, and mounted upon the rotary shaft *b*.

25 My new cleaning attachment (Fig. 2) consists of the two-part arms *c*, *d*, the front-board *e* and the claws *f*. By removing the bolts *r* the parts of each arm may be adjusted to shorten or lengthen the arm. The front-board *e* is formed with a series of holes *g* through which pass the securing bolts *h* by means of which the side arms *c*, *d* are held to the front-board *e*. It will be observed that the interval between the side-arms may be varied at pleasure by moving the arm *d* towards or from the arm *c*. The lower end of each claw *f* is bifurcated and the toes *i* straddle the discharge arm *a* (Fig. 1). The claws *f* are held in place upon the front-board *e* by means of the bolts *j* which pass through the holes *g*. It will be observed that the claws may be adjusted along

the front-board to adapt the device to discharge arms of various machines. Secured to the cross-bar *k* of the 40 breast-plate support *m* are two clips *n* the strap members *o* of which carry each a lug or ear *p* in which is pivotally mounted the end of one of the side-arms *c*, *d*.

As is clearly indicated by the dotted lines in Fig. 1, the cleaning attachment of Fig. 2 is swung upwardly, 45 as the discharge arms rotate; and the claws *f* travel over the free end of the discharge arm, freeing the latter from whatever straw may be clinging thereto. As the free end of the discharge arms move in their travel from under the claws, the cleaning attachment falls by its 50 own weight and is supported by the binder frame *q*. In case it is desired not to use the device, it may be swung over out of the way of the other parts of the binder.

My cleaning attachment may be put upon any of the 55 binders now in ordinary use and upon the market.

I claim:

1. A cleaning attachment for harvesters consisting of a pair of side-arms; a front board detachably secured to one of said side-arms and connected with the other of said 60 side-arms, said front-board being formed with a plurality of holes; and a pair of claws detachably secured to said front-board and movable along the same from hole to hole therein.

2. A cleaning attachment for harvesters consisting of a pair of two-part side-arms, the parts of each side-arm overlapping and being adjustable with respect to each other; a front-board formed with holes; bolts passing through a pair of said holes for securing said front-board to an end of each of said side-arms; and claws detachably 65 secured to said front-board and movable along the same from hole to hole therein. 70

In testimony whereof I have hereunto set my hand at said Slayton this thirteenth day of April, A. D. 1907, in the presence of the two undersigned witnesses.

CARL AMUNDSON.

Witnesses:

ALFRED TERRY,
E. A. ENGBRETSON.
